UNITED STATES PATENT OFFICE

JOSEPH C. STEINER, OF ST. LOUIS, MISSOURI

ILLUMINATING DEVICE FOR REFRIGERATORS, DISPLAY CASES, AND THE LIKE

Application filed January 14, 1928. Serial No. 246,804.

This invention relates to an improvement in illuminating devices for refrigerators, display cases and the like and has for its primary object the purpose of providing improved means adjacent the illuminating element whereby the heat caused by the element will not be effective inwardly of the refrigerator.

Another object of the invention is in providing an improvement in the housing of the illuminating element of the refrigerator whereby the heated air surrounding the element will be discharged from the housing thereby preventing heat being projected into the refrigerator.

Other and further objects will appear in the specification and be specifically pointed out in the appended claims, reference being had in the accompanying drawings, exemplifying the invention, and in which:—

Figure 1 is a vertical transverse section taken through the upper portion of a refrigerator show case showing this improved illuminating device and housing therefor.

Figure 2 is a fragmentary longitudinal section taken approximately on the line II—II of Fig. 1.

Figure 3 is a plan view of the cover plate of the illuminating housing.

Referring by numerals to the accompanying drawings 1 designates a portion of the front of a refrigerator show case having double glass walls 2 and adjoining said front portion 1 is the upper front rail 3 which forms part of the top 4 of the refrigerator, the top 4 being of the usual construction of which glass forms the major part thereof.

Transversely disposed in the top 4 between the front rail 3 and the rear rail 5 is a compartment 6 having side walls which are formed of cross members 7 of the top 4, the end walls of said compartment being provided by the front and rear rails 3 and 5 respectively, and formed in the front rail 3 is a longitudinally extending bore or passage-way 8 for the reception of electrical wiring 9.

Mounted in the rail 3 transversely thereof is a bushing 10 which extends to the bore 8, said bushing being for the reception of a socket end 11 of an electric lamp bulb 12

which is disposed longitudinally in the compartment.

The lower wall of the compartment 6 is comprised of a pair of spaced transparent glass plates or panes 13 and whereas the upper wall of the compartment is in the form of a cover plate 14 which is supported on a pair of ledges 15, each ledge being secured on a respective cross member 7. The plate 14 is provided with a pair of depending side members 16, said members being spot-welded to the plate 14, said members 16 being of the approximate length of the plate 14 and secured at 17 to said members 16 is a hood 18 the top of which is spaced from the underside of the plate 14, said hood and said side members providing a housing over the light bulb 12.

From an inspection of Fig. 2 it will be noted that the location of the side members 16 with respect to the plate 14 provides a vertical channel 19 on each side of the compartment 6, each of said channels having outward communication through the plate 14 through the row of apertures 20 in the plate 14 adjacent each side edge thereof. Formed centrally in the plate 14 are a series of apertures 21 which are in approximate alignment with the apertures 22 which are formed in the hood 18.

In the use of refrigerator show cases, it is required that some illuminating agent be effective in the show case so as to display the edible products contained therein and in which the light emitted from the bulb 12 will direct light rays from the bulb through the glass plates 13 and into the refrigerator and as the heat is radiated from the bulb the air within the hood 18 surrounding the bulb on becoming heated will rise and be discharged through the apertures 22 of the hood and through the apertures 21 of the plate 14. This displacement of heated air from the hood 18 will cause the entrainment of air to pass through the rows of apertures 20 into respective channels 19 in the direction of the arrow shown therein and the incoming air will be entrained beneath the depending side members 16, the lower edges 23 which are elevated above the uppermost

glass plate 13 and will enter the hood 18 and as the air surrounding the bulb 12 becomes heated it will pass upward through the apertures 22 and 21 and there will be a continued entrainment of air down through the channels 19 and up through the hood 18 so long as current is supplied through the electric wiring 9 through the bulb 12. This system of air circulating to and away from the bulb 12 within the housing 18 by reason of carrying the heated air away from the bulb will consequently reduce to a minimum the amount of heat which will pass through the glass plates 13 into the refrigerator.

In addition to the side channels 19, a channel 24 is provided at one end of the compartment 6 between the end plate 25 which butts against the rear end of the housing 18 and the end of the side members 16 and the end wall 26 and formed transversely in the plate 14 in alinement with the channel 24 is a series of apertures 27. The channel 24 forms a down draft passageway for air currents passing through the apertures 27.

From the description of this invention it is obvious that a unique device is provided for efficiently carrying heated air from the light emitting element or bulb and in which the walls of the channels 19 and 24 as well as the bottom plates or glass panes 13 will be cooled by the fresh air currents being entrained therethrough thereby assisting in maintaining the cooling efficiency of the refrigerator, display case or the like and consequently conserving the cooling energy thereof.

It is to be noted that a spacing is provided between the top of the housing 18 and the plate 14, this is for the purpose of preventing heat transfer from the housing to the plates.

What I claim is:—

1. A refrigerator show case or the like having a compartment formed in one of its walls, a light emitting element located in said compartment, a housing having opposing side portions overlapping said element, air entraining passageways leading to the underside of said side portions, and air escapement means leading from the top of said housing between the side portions thereof.

2. A refrigerator or the like having a compartment formed in one of its walls, a light emitting element located in said compartment, a closure plate for said compartment, a housing depended from said plate mounted over said element, a down draft passageway formed on each side of said housing in said plate leading to the underside of said housing, an air outlet formed in the top of said housing, and a transparent bottom wall for said compartment.

3. A refrigerator show case having a compartment formed in one of its walls, a housing comprising a plate having a deflector se-

cured thereto intermediate of the width of said plate, a light emitting element disposed in said compartment, said deflector having side portions which overengage respective opposing sides of the element, said plate having apertures formed therein outwardly of the side portions of said deflector and apertures disposed intermediate of the width thereof cooperable with apertures formed in the deflector, said plate forming a closure for the compartment, said side portions of said deflector providing means for directing air currents thereunder from the first mentioned apertures of said plate and to the interior of the deflector.
